UNITED STATES PATENT OFFICE

2,590,254

PORTABLE SECTIONAL IRONING BOARD

Alpha Perry Lantz, Washington, D. C.

Application January 8, 1947, Serial No. 720,813

5 Claims. (Cl. 38—104)

1

This invention relates to an improved portable sectional ironing board and has for its object the provision of such a board particularly designed for folding its sections upon themselves to bring them into superimposed relationship enabling compactness and of a size suitable for accommodation and carrying in a suitcase or similar relatively small package.

In a companion case, Serial No. 719,799, filed January 2, 1947, now Patent No. 2,558,141 the fundamental invention has been disclosed, the preferred embodiment there being means enabling the folding of the outer section under an inner section, the preferred embodiment in the present instance incorporating novel means enabling the folding of the outer section of the board over on top of the board to lie flat upon the inner section thereof.

The instant form or embodiment of the invention comprises the inner and outer sections adapted in use to have their upper or ironing surfaces flush, or in a common plane, as is quite necessary in an ironing operation, the two sections being connected by a hinging mechanism functioning, when the board is extended, to have the flush upper surfaces, as stated, but also enabling the complete folding back of the outer section onto the inner section to lie parallel with each other when in nested or stored condition.

The present invention also includes embodiments of improved means, of simple and practical character for attaching the ironing board to a convenient piece of furniture when desired for use.

The embodiments of the invention referred to are illustrated in the accompanying drawings forming part hereof and the details in the constructions will be apparent from an inspection thereof together with the detailed description hereinafter contained.

In the drawings:

Figure 1 is a top plan view of the ironing board with its sections extended as in ironing operation.

Figure 2 is an edge view of the same.

Figure 3 is a central longitudinal section through the board when folded into compact form.

Figure 4 is a transverse section on the line 4—4 of Figure 1 looking to the left.

Figure 5 is a similar view of the under or inner section of the board on the line 5—5 of Figure 3, the upper or outer section of the board being removed.

Figure 6 is a central longitudinal section through the complete board in its unfolded or extended position.

Figure 7 is a bottom view of the ironing board as illustrated in Figure 1.

2

Figure 8 is a central longitudinal section of Figure 7.

Figure 9 is a bottom view of a slightly modified form of attaching means.

5 Figure 10 is a transverse sectional view on the line 10—10 of Figure 9.

Referring more specifically to the drawings wherein like reference numerals denote the same parts in the respective views, 11 and 12 designate the two sections of the ironing board which, when in their unfolded or extended relationship have their upper surfaces flush or in a common plane, and contoured to present a combined shape for use after the fashion of a customary ironing board.

10 The section 11 has an end extension 13 of considerable length and extends entirely across the section, the same being depressed as at 14 for a depth equal to the thickness of the board 12 to provide a seat for the meeting end whereby the operating surfaces of the sections 11 and 12 will be in a common plane when being ironed upon.

15 These sections 11 and 12, and other parts of the ironing board, will be formed of some light material, such as metal, aluminum, or plastics, easily carried and preserved against rust, staining or the like.

20 When not in use, and to enable storage or carrying of the board from place-to-place in travel, the sections 11 and 12 are hinged together as will now be pointed out.

25 It is to be noted that the outer section 12 has a surrounding depending flange 15 to strengthen the same and at the inner ends to receive the end 13 of the section 11; and that the latter (the section 11) has a corresponding depending flange 16 surrounding the side edges and the inner end thereof with inwardly turned lower portions or flanges 17 to further strengthen said section. The flanges 16 of the side edges of section 11 are of less depth than the flange 16 of the end (see Figure 5). The outer end of the section 11, as at 18 is oppositely depressed inwardly to receive the end portions of the flange 15 on the section 12 so that the outer faces of the meeting flanges will be smooth or flush to avoid projecting edges to catch upon the apron or clothes of the operator.

30 Opposite ends 20 of a hinge rod 21, extending across and located beneath the section 11, project outwardly and have pivotal bearing in the vertical portions of the flanges 16, spacing sleeves 19 through which said ends 20 pass to said wall, abutting the inner faces of the flanges and offset U-shaped hinge portions 22 to prevent objectionable endwise play. The offset U-shaped hinge portions 22 pass through the free ends 23 of companion hinge members 24 in the form of inte-

gral extensions from the section 12 passed around the offset portions 22 and riveted at their return ends to the section 12 at 25. The hinge members 24 while extending from the surface of the section 12 are dipped sufficiently near their pivoted ends as at 26 to pass through accommodating openings 27 in the section 11, to underlie and abut the top of the section 11 when the sections are unfolded and extended in ironing position (Figure 6), said openings 27 being extended outwardly to permit passage of the hinge ends 23 and offsets 22 of the pivot rod in an upward direction to enable folding of the outer section 12 back flat upon the inner section 11 (Figure 3), when the board is not in use and is to be stored or carried in a suitcase or package.

The portions of the side flanges 16, of the section 11, are widened downwardly as at 28 to afford sufficient metal and corresponding strength at the pivoted end portions 29 of the rod 21 therewith.

The sectional, foldable feature of the ironing board, as above described, will not be claimed herein inasmuch as the same is made the subject matter of a co-pending divisional application.

This divisional application was filed April 5, 1948, and bears Serial No. 19,077.

Of course, the inner section 11 of the board must be provided with the means for supporting the same with the outer section when in ironing position and for this purpose a novel adjustable attaching means is associated with the section 11, designed for enabling the board to be rested upon and supported by a convenient drawer or the like of furniture usually at hand in hotel rooms, apartments and the like. As is well-known, an ordinary desk, for example, has a drawer with a front wall of substantial thickness at the top affording a flat upper edge on which the ironing board may be supported when the drawer is withdrawn for that purpose, and above the drawer there is a bridge piece behind which the ironing board may be hooked or anchored when the board is supported in operative position on the front wall of the drawer as stated.

With this in view the inner section 11 for a portion of its inner end has its horizontal flanges 17 extended inwardly for a substantial distance as at 29 and may be offset at 31 or not as desired, to provide longitudinal ways 30 for the shanks 36 of hooks 32 adapted to be engaged in rear of the said bridge piece or its equivalent, the hooks having pivoted upwardly extending parts 33 adapted when not in use to fold down in parallel relation to the upper surface of the section 11 (Figures 1 and 2) and when in use to be swung upwardly into vertical position to constitute extensions of the hooks 32 (Figures 3, 6 and 8) to be engaged behind the bridge piece as will be obvious.

The hooks 32 and their shanks are extended from the section 11 in a plane near the bottom edge of the section, depressed portions 34 of the shanks being provided for such purpose so that the board when supported on the edge of the drawer will be positioned in a horizontal plane. The depressed portions 34 of the shanks 36 will pass under the bridge piece referred to which is usually in approximately the same horizontal plane as the edge of the drawer. The depressed portions 34 of the shanks pass inwardly through appropriate apertures 35 in the inner end wall

of the flange 16 of the section 11, immediately above the horizontal or terminal flange portion 17 thereof. The outermost ends of the shanks 36, that is, the higher portions thereof (see Figure 6) are enlarged transversely as indicated at 36 to confine said ends in the spaces intermediate the ironing face or top of the section 11 and the flanges 29, between which latter the shank portions 36 work.

10 In each instance, welded or otherwise secured at 31 to the rise 38, between the depressed portion 34 and the elevated outer ends of the shanks 36, is an upwardly tending spring 39 provided with a pull ring 40 to cause the spring to be drawn downwardly to release the offsets or shoulders 41 on the free end of the spring from engagement behind depending lugs or stops 42 depending from the flanges 29 when the shanks and hooks are being disengaged for longitudinal adjustment, it being observed that there are two series of these depending lugs or stops, in each instance, to be automatically engaged by the upwardly springing shoulder portions 41 when the adjustment has been effected as desired, and the parts held in adjusted position.

In Figures 9 and 10 a slightly different or modified construction is illustrated wherein the ways 43 are formed as extensions of the reinforcing flanges 47 of the board section 11, which ways 30 consist of offset portions 45 having guides 44 stamped therefrom forming chambers to receive the outer ends of the shank portions 36 of the hooks. These guides 44 contact the under side of section 11, as at 46. Also stamped from the offset portions 45 are the stop lugs 48 which are engaged by spring catches 49 carried by the hook shanks to retain the hooks in adjusted position. In order to add rigidity to the ways 43 the edge portions of the offset portions 45 are welded to the underside of section 11, as at 51 and 46 (Figure 10).

The same is true of the offset portions 52 and 53 in the first-mentioned form of device illustrated in the first series of figures of the drawings (see Figure 7) which flanges 52 and 53 are welded or otherwise secured to the top of the section 11 in the embodiment therein illustrated. Thus, in either embodiment of the invention, a very rigid guiding structure and stop adjustment for the hooks and their shanks, is constituted. Suitable pads of rubber or other material, designated at 59 may be carried on the relatively wide portions of side flanges 17 to rest upon the top of the drawer in protecting the same against scratching or marring the furniture, and similar rubber pads or coverings 57 and 58 may be used to cover the upper faces of the inner corners and end of the section 11 to similarly protect the furniture when the ironing board is carelessly being inserted in the drawer opening from over the top of the drawer and hooked behind the bridge piece.

I claim:

1. A portable ironing board and means for temporarily attaching the same to a supporting article of furniture, comprising a board having side edges reinforced by flanges extending downwardly and inwardly of the board, said inwardly extending flanges being increased in width adjacent one end of the board and having guide parts struck upwardly to the bottom of the board to provide shallow guide chambers beneath said board, hooks for attaching the board to the article of furniture provided with shanks passing through guide openings in the downwardly and

inwardly extending reinforcing flanges of the board end, said shanks having portions lying approximately in the same plane as the lower edges of the board enlarged end portions slidably received in said chambers and intermediate portions angularly disposed with reference to the other named portions of the shanks, and latch means carried by the shanks to hold the hooks in adjusted position.

2. A portable ironing board and means for temporarily attaching the same to a supporting article of furniture, comprising a board having side edges and an end reinforced by flanges extending downwardly and inwardly of the board, said inwardly extending flanges of the side edges having offset portions increased in width adjacent said end of the board and having guide parts struck upwardly to the bottom of the board to provide shallow guide chambers beneath said board, said portions of the flanges having the increased width being provided with longitudinally extending slots therein, hooks for attaching the board to the supporting article of furniture having shanks passing through guide openings in the downwardly and inwardly extending reinforcing flanges of the board end, said shanks having portions lying approximately in the same plane as the lower edges of the board, enlarged end portions slidably received in said chambers and intermediate portions angularly disposed with reference to the other named portions of the shanks, said intermediate portions passing through said slots, and latch means carried by said shanks to hold the hooks in adjusted position.

3. A portable ironing board and means for temporarily attaching the same to a supporting article of furniture, comprising a board having side edges and an end reinforced by flanges extending downwardly and inwardly of the board, said inwardly extending flanges of the side edges having offset portions increased in width adjacent said end of the board and having guide parts struck upwardly to the bottom of the board to provide shallow guide chambers beneath said board, said portions of the flanges having the increased width being provided with longitudinally extending slots therein, the downwardly and inwardly extending reinforcing flanges of the board end being of greater depth than like flanges of the side edges and provided with guide openings adjacent to the lower edge, hooks for attaching the board to the supporting article of furniture having shanks passing through the guide openings, said shanks having portions lying approximately in the same plane as the lower edges of the board, enlarged end portions slidably received in said chambers and intermediate portions angularly disposed with reference to the other named portions of the shanks, said intermediate portions passing through said slots, said hooks being vertically positioned and pivotally connected to the end portions of the shanks to swing toward the board whereby said hooks may lie parallel with the board when not in use, said hooks having downwardly directed extensions which engage the end portions of the shanks to prevent said hooks from swinging in a direction away from said board when in use, and latching means carried by said shanks to hold the hooks in adjusted position.

4. A portable ironing board and means for temporarily attaching the same to a supporting article of furniture, comprising a board having side edges and an end reinforced by flanges ex-

tending downwardly and inwardly of the board, said inwardly extending flanges of the side edges having offset portions increased in width adjacent said end of the board and having guide parts struck upwardly to the bottom of the board to provide shallow guide chambers beneath said board, said portions of the flanges having the increased width being provided with longitudinally extending slots therein, latch lugs adjacent said slots, the downwardly and inwardly extending reinforcing flange of the board end being of greater depth than like flanges of the side edges and provided with guide openings adjacent to the lower edge, hooks for attaching the board to the supporting article of furniture having shanks passing through the guide openings, said shanks having portions lying approximately in the same plane as the lower edges of the board, enlarged end portions slidably received in said chambers and intermediate portions angularly disposed with reference to the other named portions of the shanks, said intermediate portions passing through said slots, said hooks being vertically positioned and pivotally connected to the end portions of the shanks to swing toward the board whereby said hooks may lie parallel with the board when not in use, said hooks having downwardly directed extensions which engage the end portions of the shanks to prevent said hooks from swinging in a direction away from said board when in use, and latching means carried by said shanks engaging said lugs to hold the hooks in adjusted position.

5. A portable ironing board and means for temporarily attaching the same to a supporting article of furniture, comprising a board having side edges and an end reinforced by flanges extending downwardly and inwardly of the board, said inwardly extending flanges of the side edges having portions increased in width adjacent said end of the board and having guide parts struck upwardly to the bottom of the board to provide shallow guide chambers beneath said board, said portions of the inwardly extending flanges having the increased width being provided with longitudinally extending slots, latch lugs adjacent said slots, hooks for attaching the board to the supporting article of furniture having shanks passing through openings in the downwardly and inwardly extending reinforcing flanges of the board end, said shanks having portions lying approximately in the same plane as the lower edges of the board, enlarged end portions slidably received in said chambers and intermediate portions angularly disposed with reference to the other named portions of the shanks, said intermediate portions passing through said slots, and latches carried by said shanks to engage the latch lugs.
